Primary Examiner — Cynthia R Underwood(74) Attorney, Agent, or Firm — Robert M. Chiaviello, Jr.(57) CLAIM

An ornamental design for a rectangular feeding mat, as shown and described, except as disclaimed herein.

DESCRIPTION

FIG. 1 is a top view according to the rectangular feeding mat presented herein;

FIG. 2 is a front plan view with the back plan view being identical;

FIG. 3 is a left plan view with the right plan view being identical; and,

FIG. 4 is a perspective view.

The broken lines in the drawings depict environmental subject matter that is hereby disclaimed and forms no part of the claimed design.
